CLAIM

The ornamental design for a remote control with charger, as shown and described.

DESCRIPTION

FIG. 1 is a exploded perspective view of a remote control with charger, showing my new design;

FIG. 2 is a perspective view showing the remote control placed in the charger;

FIG. 3 is a front view of FIG. 2;

FIG. 4 is a rear view of FIG. 2;

FIG. 5 is a top view of FIG. 2;

FIG. 6 is a bottom view of FIG. 2;

FIG. 7 is a right view of FIG. 2; and,

FIG. 8 is a left view of FIG. 2.

The dotted line showing of a cord is for illustrative purposes only, and forms no part of the claimed design.
